UNITED STATES PATENT OFFICE.

MORTIMER FRANKEL, OF CHICAGO, ILLINOIS, ASSIGNOR TO WILMORT MANUFACTURING COMPANY, OF CHICAGO, ILLINOIS, A CORPORATION OF ILLINOIS.

DESIGN FOR A CRUMB-SWEEPER.

51,639.

Specification for Design.

Patented Jan. 1, 1918.

Application filed October 22, 1917. Serial No. 197,968. Term of patent 7 years.

To all whom it may concern:

Be it known that I, MORTIMER FRANKEL, a citizen of the United States, residing at Chicago, in the county of Cook and State of Illinois, have invented a new, original, and ornamental Design for a Crumb-Sweeper, of which the following is a specification, reference being had to the accompanying drawing, forming part thereof.

I claim:

The ornamental design for a crumb sweeper as shown.

MORTIMER FRANKEL.
